[57] CLAIM

The ornamental design for an ashtray, as shown.

DESCRIPTION

FIG. 1 is a perspective view of the ashtray taken from above and showing our design;
FIG. 2 is a plan view of FIG. 1;
FIG. 3 is a bottom view of FIG. 1;
FIG. 4 is an elevational view drawn to a smaller scale of FIG. 1; and
FIG. 5 is an elevational view similar to FIG. 4 showing another embodiment of our design.

FIG. 1

FIG. 4
